SAFETY EQUIPMENT FOR FUEL TANKS

Teron D. Whidden, Jacksonville, Fla.

Application November 2, 1949, Serial No. 125,139

7 Claims. (Cl. 220—88)

1

This invention relates to safety devices and more specifically to apparatus for protecting a tank containing an inflammable liquid or gas from fire or explosion. This application is a continuation-in-part of application Serial No. 646,921 filed February 11, 1946, by T. D. Whidden, now Patent No. 2,552,472, issued May 8, 1951.

It is an important object of this invention to improve the safety of tanks containing inflammable gas or liquid, particularly the tanks of bulk fuel delivery trucks and the like.

The conventional bulk fuel delivery truck tank has many fire and explosion hazards. These tanks are customarily filled to a designated or predetermined level or mark, leaving a portion of the upper section of the tank to be filled by expansion of the fuel. It is obvious that any overflow or leakage of the inflammable fuel constitutes a serious fire hazard. Moreover, these tanks, through negligence, are often filled beyond or above the designated mark, thereby taking up all or a portion of that space intended as a safety factor and as a means for saving fuel.

Furthermore, these conventional bulk fuel delivery truck tanks have another disadvantage in that they have restricted vacuum relief when unloading fuel, causing the operator to open the fill cap to relieve the restricted condition and this action increases the danger of ignition of inflammable vapors which may cause an explosion.

Another common fault of conventional bulk delivery tanks is the constant danger from sparks or flame near their vents. No known existing truck tank arrangement provides positive flame arrestor action through the vents at all times.

Still another fault or fire hazard of such conventional truck tanks is the extreme danger of refilling them due to the fact that when the tank has been unloaded the space formerly occupied by the fuel has been replaced by air and under certain conditions a mixture of fuel vapor and air is very explosive needing only a spark of any type (such as a static spark or one caused by human negligence) to ignite it. The danger of static spark is recognized to the extent that a chain is usually required by law to attempt to ground the static electricity. While it has been suggested that the fuel be replaced by carbon dioxide or other non-oxidizing gas, this is rarely done in practice due to the complexity or high cost of existing arrangements or to their unreliable action or to the necessity for their maintenance.

It is another object of this invention to reduce or eliminate the above-mentioned disadvantages of fuel tanks for trucks.

2

The above and related objects are attained in accordance with the invention by providing various safety systems for protecting a tank containing an inflammable liquid or gas from fire or explosion. These systems are particularly adaptable for bulk fuel delivery truck tanks but may be used with other types of tanks as well. A feature of all of the systems disclosed herein is the provision of an expansion chamber of predetermined or calibrated size partially within the fuel tank. This reduces the height required for the installation.

In one exemplary embodiment of the invention, the expansion chamber partially within the fuel tank has its inlet at a higher level than the fuel tank inlet (so that no fuel can enter the expansion chamber while the tank is being filled) and has its outlet (at the top of the expansion chamber) connected to an auxiliary expansion chamber at the side of the fuel tank. The auxiliary expansion chamber is positioned and connected between two flame guard chambers partially filled with a non-inflammable liquid. One of the flame guard chambers is connected to the exhaust pipe of the truck engine while the other is connected to the atmosphere. Each flame guard chamber is provided with a bell chamber having a multiplicity of small holes therein to reduce the size of the bubbles in the liquid.

If desired, the bulk fuel tank can have a divided construction and two or more expansion chambers provided, one for each division of the fuel tank. One of these modifications is provided with mechanical check valves while the other does not have such valves.

The invention will be more readily understood by referring to the following description taken in connection with the accompanying drawings, in which:

Fig. 1 is an elevation view, with portions in cross-section, of a bulk delivery fuel tank with an improved safety arrangement in accordance with the invention;

Fig. 2 is a top view of the arrangement of Fig. 1; Fig. 3 is an elevation view, with portions in cross-section, of a modification of the arrangement of Fig. 1; and

Fig. 4 is an elevation view, with portions in cross-section, of a modification of the arrangement of Fig. 3.

Referring more specifically to the drawings, Figs. 1 and 2 show, by way of example for purposes of illustration, a bulk fuel delivery tank 10 and safety apparatus therefor, in accordance with the invention, which will be described below.

The tank 10 is, by way of example, of the type used by trucks for the transportation of fuel in

bulk but it will be appreciated that certain features of novelty of the present invention are applicable to other types of tanks as well. The tank 10 has a filler cap 11 and a withdrawal or delivery line 12 having a valve 13 therein.

The safety apparatus for the tank 10 will now be described. Positioned almost, but not entirely, within the confines of the tank 10 is an expansion chamber 14, the upper portion 15 of the chamber 14 extending above the filler opening closed by the cap 11. A connecting line 16 extends from the top part of the tank 10 almost to the bottom 17 of the chamber 14. From the extreme top of the chamber 14 a pipe line 18 connects with an auxiliary expansion chamber 19. From the top of chamber 19 a pipe line 20 extends into and nearly to the bottom of side chamber 21 while another pipe line 22 connects from the chamber 19 to the top of side chamber 23. The pipe 24 extends from the lower portion of chamber 23 out through the top of this chamber to the exhaust pipe 25 of the truck. The pipe lines 24 and 20 extend below the surfaces of the liquid (such as glycerine) 30 and 31 in the chambers 23 and 21, respectively, and are connected, respectively, to the bell chambers 26 and 27 therein. Each bell chamber has a multiplicity of apertures 28 therein. From the top of chamber 21 a line 29 opens to the atmosphere. The chambers 19, 21 and 23 and the connecting lines thereto and therefor are all external of the tank 10. The use of glycerine is particularly valuable due to its anti-freeze qualities and since it is mixable with water but not with gasoline. Its weight and viscosity also make it suitable for the purpose.

The expansion chamber 14 is calibrated for a predetermined rate of fuel expansion, such as 3 percent for example. Since the line 16 extends above the filler opening closed by the cap 11, even if the tank 10 is filled completely full and the filler cap is screwed on tight, no fuel can reach the expansion chamber 14 during the filling operation even if the operator is careless enough to overflow the tank. For this reason, this predetermined margin of safety for expansion is absolutely available even if the operator is careless or negligent in filling the tank.

As the temperature rises and the fuel in the tank 10 increases in volume, the excess flows through pipe 16 into the expansion chamber 14. This displaces the air in the chamber 14, causing an increased pressure of air in line 15 and also in lines 20 and 22. Thus, pressure applied to the surface of the liquid in chamber 23 raises the level of the liquid in line 24 equal to the distance that an equivalent pressure forces the liquid down in line 20 inside of chamber 21. As the pressure forces the liquid down further in line 20 into bell chamber 27, air escapes through the openings 28, bubbling up through the liquid 31 and the line 29 to the atmosphere. The purpose of the bell chamber 27 is to allow a large area for many small holes 28 thus causing smaller bubbles and less agitation or splash of liquid seal.

Consideration will now be given to the reverse operation, that is to contraction of the fuel in the main tank 10 or to the opening of the delivery valve 13 (either of which will cause a partial vacuum in the main tank). This partial vacuum draws or lifts any excess fuel in chamber 14 back into the main tank 10 through line 16. The same partial vacuum is applied to line 15, chamber 19, lines 22 and 20 and lifts the liquid up in line 20 the same distance that it pulls the liquid level down in line 24 into bell chamber 26, thus

opening the holes 28 and allowing the engine exhaust gases from the pipe 25 to enter. Any carbon or dust particles are trapped in the liquid in chamber 23 and settle on the bottom of this chamber where they cannot interfere with passage of gases. The chamber 19 acts as a trap for any splash of liquid seal from either chamber 21 or 23 to prevent it from entering the expansion chamber 14. It also has the function of trapping any overflow (caused by excessive expansion of fuel) from the chamber 14. Any fuel entering chamber 19 will not return to the main tank 10 and examination of the amount of fuel therein will provide a reading, if desired, which can be used to ascertain whether the tank 10 is large enough for the installation. The chamber 19 can be drained by means of the opening 32.

The arrangement shown in Fig. 1 can also be used to force fuel from the main fuel tank 10 by providing the cut off valve 33 in the line 25. Since lines 24, 22, 18, 16, 20 and 29 are of equal size piping, which is also the same as that used for the gas pipe 25, it is perfectly safe to apply the pressure of the engine exhaust to the tank 10. By closing or partially closing valve 33 in exhaust pipe 25, the pressure of exhaust gas is routed through line 24, the liquid 30, and line 22 to chamber 19. Pressure is built up to a point sufficient to force glycerine down in line 20 into bell chamber 27, before escaping to the atmosphere through the glycerine 31 and line 29. The pressure that was exerted in line 20 is also applied to line 15 and, of course, to the tank 10 and its contents. If the drain valve 13 is open and the gases are insufficient in volume to replace the liquid being drawn off, the weight of the glycerine will close line 20. Speeding up the motor of the truck is not dangerous since this will again open line 20. Line 20, chamber 21, glycerine 31 and line 29 form a low pressure relief or check valve. Line 24, chamber 23, glycerine 30 and line 22 form a low stage vacuum relief or check valve. This feature of utilizing the compression of the exhaust engine gases to force fuel from the tank 10 is very valuable. It also prevents any possibility of explosion of the tank 10 by flame, spark or static electricity. Since this arrangement will unload the bulk fuel more quickly when the fill cap 11 is closed, the driver will have no reason to leave the cap off. Moreover, since the arrangement of Fig. 1 can (by the pressure of the exhaust gas) lift the fuel to a delivery point higher than the level in the tank, in many cases it takes the place of a delivery pump. It also has positive flame arresting on inhaling and exhaling openings and no mechanical check valves are necessary since the liquid in the flame guard chambers 21 and 23 serves as liquid check valves. This liquid quenches any sparks which may be present if conventional pumps are used to force or transmit stack, flue or engine exhaust to the fuel tank.

Figs. 3 and 4 show modifications suitable for divided tanks but it will be obvious that some features are applicable to single chamber fuel tanks as well. In Fig. 3, the tank 10 comprises two divisions 40 and 41. Partially within each of the divisions is an expansion chamber 42 (or 43). Each of these two chambers has an inlet pipe 44 (or 45) opening into the top of the fuel tank 10 and a drain pipe 46 (or 47) having a check valve 48 (or 49) therein. A drain 50 is provided for the tank 10 and the expansion chambers 42 and 43 have their upper portions connected to the pipe 51 which is a vent line to a flame guard chamber or to an auxiliary expansion

chamber such as the chamber 19 in Fig. 1 or is opened directly to the atmosphere or to a source of carbon dioxide such as the pipe 24 in Fig. 1. Caps 52 and 53 are provided to fill the divisions 40 and 41. The expanded fuel flows into the chambers 42 and 43 and when the fuel contracts it flows back into the tank 10 through the check valves 43 and 49. In the arrangement of Fig. 4, no mechanical check valves are required as the pipes 60 and 61 from the main tank 10 to the expansion chambers 42 and 43 are carried almost to the bottoms of the chambers 42 and 43. In this arrangement, the expanded fuel reenters the tank 10 through pipes 60 and 61 in a manner similar to that described above in connection with pipe 16 of Fig. 1. Otherwise the operation is the same as that of the arrangement of Fig. 3.

Various other modifications are possible without departing from the spirit of the invention, the scope of which is indicated in the claims. In the claims, the term "gas" is intended to cover a mixture of gases, such as air.

What is claimed is:

1. A safety system for a liquid fuel tank having a filler opening at the top thereof, comprising a closed expansion chamber at least the major portion of which is within the confines of the outer walls of said fuel tank, said expansion chamber being normally free of liquid, a connection from the upper portion of said tank into the top portion of said chamber and extending to a point near the bottom thereof, a portion of said connection being at a higher level than said filler opening to prevent entrance of liquid into said expansion chamber should said tank be filled to overflow said filler opening, and said top portion of the expansion chamber having connections to the atmosphere for both pressure relief and vacuum relief.

2. A safety system for a liquid fuel tank having a filler opening at the top thereof, comprising a closed expansion chamber at least the major portion of which is within the confines of the outer walls of said fuel tank, a connection from the upper portion of said tank to said chamber, a portion of said connection being at a higher level than said filler opening, a flame guard chamber adjacent said tank and containing non-inflammable liquid, means for admitting inert gas to said flame guard chamber, and pipe means for connecting said flame guard chamber to said closed chamber, said gas admitting means including a bell chamber having a plurality of apertures therein submerged within the liquid of said flame guard chamber.

3. A flame guard chamber comprising a closed tank adapted to contain non-inflammable liquid, an opening in the top of said tank, a second opening in the top of said tank, a pipe adapted to have inert gas applied thereto projecting through said second opening and extending almost to the bottom of said tank, and a bell chamber connected to the lower end of said pipe, said bell chamber having a plurality of small apertures therein.

4. In combination, a tank adapted to contain an inflammable fluid, a hollow container which is normally free of liquid and which is at least partially within said tank, means connecting the upper part of said tank to the upper part of said container in such a way that fluid will not enter the hollow container should the filler opening be caused to overflow and that when fluid in said tank expands or overflows it flows into said container, drain means in the lower part of said

container for draining fluid therein into said tank, said drain means having a check valve therein to prevent the entrance of fluid into said hollow container through said drain means, and

5. means for admitting non-inflammable gas into said container when the fluid is being reduced in volume and for directing the flow of said gas from said container when the fluid is being expanded.

10 5. A safety system for a liquid fuel tank having a filler opening at the top thereof, comprising a closed expansion chamber at least the major portion of which is within the confines of the outer walls of said fuel tank, a connection from the upper portion of said tank to said chamber, an auxiliary expansion chamber at the side of said fuel tank, a pipe connection from the upper part of said first expansion chamber to said auxiliary expansion chamber, a flame guard chamber on each side of said auxiliary expansion chamber, and pipe connections from the flame guard chambers to said auxiliary expansion chamber.

15 6. A safety system for a liquid fuel tank having a filler opening at the top thereof, comprising a closed expansion chamber at least the major portion of which is within the confines of the outer walls of said fuel tank, a connection from the upper portion of said tank to said chamber, a portion of said connection being at a higher level than said filler opening, a liquid check valve

20 30 35 40 chamber adjacent said tank and containing non-inflammable liquid, pipe means for connecting said chamber to top of said closed chamber and pipe means for connecting and transmitting pressure relief to the atmosphere, a second liquid check valve chamber adjacent said tank and containing non-inflammable liquid, pipe means for connecting said chamber to the top of said closed chamber, and pipe means for admitting inert gases into said second liquid check valve chamber and transmitting vacuum relief to said tank.

45 7. A safety system for a liquid fuel tank having a filler opening at the top thereof, comprising a closed expansion chamber at least the major portion of which is within the confines of the outer walls of said fuel tank, said expansion chamber being normally free of liquid, a connection from the upper portion of said tank into the top portion of said chamber and extending to a point near the bottom thereof, a portion of said

50 55 60 connection being at a higher level than said filler opening to prevent entrance of liquid into said expansion chamber should said tank be filled to overflow said filler opening, a second expansion chamber, a connection from the top portion of said first expansion chamber to the top portion of said second expansion chamber, and connections from the top portion of the second expansion chamber to the atmosphere for both pressure relief and vacuum relief.
